FRED E. ADAMS, OF PROVIDENCE, RHODE ISLAND, ASSIGNOR TO U. S. BOBBIN & SHUTTLE COMPANY, OF PROVIDENCE, RHODE ISLAND, A CORPORATION OF RHODE ISLAND

SHUTTLE TENSION

Application filed April 9, 1928. Serial No. 268,508.

This invention pertains to loom shuttles and more particularly to a yarn tension device applicable to a self-threading shuttle eye of usual type. It is very desirable, usual, 5 and in most cases necessary, particularly when dealing with hard, wiry, or stiff yarns which tend to balloon off freely from the end of the bobbin, to provide restraining means for preventing the uncontrolled escape of the 10 yarn through the shuttle eye with consequent snarling and breakage of the yarn and imperfect weaving. While some such restraining or tension means is in most instances essential to satisfactory operation of the 15 shuttle, it is not an easy matter to provide adequate tension means in the limited space available, especially in a shuttle having an eye of self-threading type where the tension device must not interfere with automatic 20 threading. A common form of tension device employed in shuttle eyes of this character consists simply of a piece of felt or other friction material over which the yarn drags, but such an arrangement is not at all certain 25 in its action, provides no positive or regulable control of the yarn, does not always exert the same tension or drag in both directions of movement of the shuttle, and varies in its frictional resistance to the movement of the 30 yarn in accordance with atmospheric conditions and its length of use. The inadequacy of this type of tension is especially evident when dealing with smooth, hard or wiry 35 yarns, for example twisted silk.

I am aware that true tension devices, as distinguished from mere felt pads or the like, have been suggested for use in shuttles, but most such devices known to me have proven inadequate, either through interference with 40 the automatic threading operation, lack of adjustability to permit variation of tension or to accommodate yarns of different diameters, or by reason of complexity of construction with attendant excessive cost, and especially in their inability long to withstand the 45 cutting action of fine and hard yarns and the difficulty of replacing worn parts.

In accordance with the present invention 50 I provide a tension device applicable to self-threading shuttle eyes of a well-known type,

without necessitating substantial modification of the latter, and which does not in the least interfere with or delay the threading operation; which is readily adjustable to vary the tension or to accommodate yarn of different numbers; which exerts a positive, unvarying, and predetermined pressure and drag upon the running yarn; which exerts substantially the same tension on the yarn in either direction of movement of the shuttles; 55 which is very simple and inexpensive to construct and apply, and whose yarn-engaging parts may readily be made of extremely hard and wear-resistant material, and which, if eventually worn, may be replaced quickly 60 and without difficulty.

In the accompanying drawings I have illustrated a preferred embodiment of the invention by way of example and in the drawings,

Fig. 1 is a fragmentary plan view showing the eye-end of a loom shuttle provided with a self-threading eye embodying the present invention;

Fig. 2 is a side elevation of the shuttle of Fig. 1, showing the lateral yarn-delivery opening;

Fig. 3 is a side elevation, from the same side as Fig. 2, showing the shuttle eye removed from the shuttle body;

Fig. 4 is a side elevation of the shuttle eye from the opposite side;

Fig. 5 is a vertical section, to larger scale, on the line 5—5 of Fig. 1, with parts broken away;

Fig. 6 is a perspective of the upper, movable, tension element;

Fig. 7 is a perspective view of the lower tension element;

Fig. 8 is a perspective view showing another form of lower tension element, and

Figs. 9 and 10 are perspective views illustrating, respectively, other forms of upper tension element.

Referring to the drawings, the shuttle body 1, which may be of wood or of other suitable material, is furnished as usual with the pointed end cap 2 and with the bobbin cavity 3 in which is arranged the bobbin 4 supporting the yarn mass 5. The shuttle

body is also provided with a cavity 6 for the reception of the removable, self-threading shuttle eye 7, and one side wall of this cavity is furnished with the lateral delivery opening 8, provided, as is usual, with wear-resistant guide posts 9 and 10 at its opposite sides. A bolt 11 normally retains the metallic shuttle eye 7 in proper position in the usual manner.

- 10 The shuttle eye 7 (Figs. 3 and 4) is here shown as of substantially usual construction, comprising the base portion 12 having a longitudinal passage or channel 12^a for the yarn Y, and an upper part comprising the 15 overhanging guard member 13 spaced from the side wall of the yarn guide channel to provide the usual lateral entrance to said channel; the lateral horn 14 which fits into a suitable recess in the shuttle body; and the 20 forward horn 15 which assists in guiding the thread into the thread passage. The upper part of the shuttle eye also carries a depending guide prong 16 at its forward end, while the side wall of the thread-guiding channel 25 is furnished at its forward end, beyond the end of the channel, with an upstanding guard portion 17.

In accordance with the present invention I cut away a portion of the base 12 of the 30 shuttle eye to provide a rabbet or recess at 18. I then provide a lower tension element, preferably consisting of a plate or block 20, constituting a yarn support, such block or plate being cut away to provide a thin portion 19 which fits into the rabbet or recess 18 in the base of the shuttle eye, and a shoulder 21 which fits snugly against the forward surface 22 of the base 12 of the shuttle eye. Preferably the shoulder 21 comprises an inclined or diagonal portion 23 which engages the forward edge of the part 17. The upper edge of the shoulder portion 23 is preferably rounded or beveled to assist in guiding the thread beneath the upper tension element, hereafter described. The body or thick portion of the yarn support 20 is furnished with a smooth upper surface constituting the yarn support proper which is preferably slightly above the bottom of the yarn channel in the 50 base 12. This block is preferably made of alloy steel or some similar substance, preferably heat-treated to make it very hard, and capable of withstanding the cutting action of the rapidly moving yarn. The yarn support 20 is placed in the cavity of the shuttle body, resting firmly on the bottom 6^a of the cavity and being retained in position solely by the superposed shuttle eye.

The block 20 is furnished with a vertical 60 opening 24 for the reception of the lower end of a hard and wear-resistant guide pin 25. This pin 25 is provided with a cylindrical head 26 of larger diameter than the lower part of the pin, thereby providing a shoulder 65 at the point 27. The head 26 is screw

threaded and engages an internally screw-threaded opening 28 in the upper part of the shuttle eye 7 at a point such that the axis of the pin is disposed substantially in the vertical longitudinal plane of the prong 16, 70 between the latter and the forward end of the yarn channel in the base 12. The upper end of the pin is provided with a slot 29 for the application of a screw driver by means of which the pin may be adjusted vertically. The axis of the pin is also substantially in the vertical plane extending transversely of the shuttle through the center of the delivery opening 8, and this pin defines the point in the yarn path where the yarn makes an abrupt substantially right angular turn on its way to the delivery opening. Preferably the pin is of such length that its lower end indents the wood of the shuttle body, thus providing a bearing which 80 steadies the pin and the tension elements. 85

The yarn is pressed against the upper surface of the yarn-supporting block 20 by means of an upper tension element 30. This upper tension element comprises an annular lower part or friction-shoe 31, preferably provided with a substantially flat and smooth under surface, and having a central opening for the passage of the pin 25. The upper portion of this opening is enlarged to furnish a socket 32 for the reception of a resilient element 33. This resilient element may be a coil spring or other suitable device, but as here shown consists of a short section of rubber tubing which slipped onto the pin 25 and bears at its upper end against the shoulder 27, and at its lower end against the bottom of the socket 32. The member 30 is concentric with the pin or post 25 and immediately behind prong 16 and is of such diameter that it does not substantially restrict the lateral entrance to the yarn channel. 95

The upper tension element 30 also comprises an upstanding guide portion 34, which is here shown as a thin cylindrically curved shell of substantially semi-circular extent whose upper portion preferably embraces and slidably engages a boss 7^a on the shuttle eye. This guide member 34 is disposed in spaced relation to the guard member 17 above referred to, and serves as a guide for the thread during the threading operation, preventing the thread from catching on the top of the shoe 31 as the thread moves vertically between the shuttle wall and the shuttle eye. The friction-shoe 30 may be made of any suitable material capable of resisting wear, preferably of very hard steel, and its under surface, as well as the upper surface of the yarn-supporting block 20, is preferably flat and smooth, although these surfaces may be roughened if desired or otherwise shaped or finished to secure the desired frictional resistance to the passage of the yarn. Preferably the lower edge or junction of the flat 100 105 110 115 120 125 130

under surface and curved peripheral surface of the shoe 31 is beveled or rounded as indicated at 31^a to facilitate entry of the yarn beneath the shoe.

5 The position of the pin 25 is so chosen, as above described, that a yarn disposed between the members 20 and 31 makes a substantially right-angle turn in passing around the pin and out through the delivery opening 8.

10 When the yarn Y is drawn off from the thread mass on the bobbin and pulled forwardly over the upper surfaces of the members 13 and 15, it slips down between the members 17 and 34 and into the yarn passage 15 in the base 12. The yarn is then drawn laterally between the shuttle body and the member 14 into the opening 8. The yarn now rests upon the upper surface of the block 20, such surface being slightly above the bottom of 20 the yarn passage, and in the horizontal plane of the delivery opening 8, and as tension is applied, the lateral pressure of the yarn against the beveled edge 31^a of the shoe 31 lifts the latter against the tension of the member 25 33 and permits the yarn to enter between the upper and lower tension elements and to wrap around pin or post 25. The beveling of the upper corner of the shoulder 23 also facilitates the entry of the yarn beneath the shoe 31.

30 During the operation of the shuttle, the yarn is drawn off between the members 20 and 31, and the resilient pressure of the member 33 accurately determines the frictional resistance opposed to the movement of the 35 yarn. By adjusting the height of the pin 26, the tension of the member 33 may be varied and thus the pressure on the yarn may be fixed as desired.

While the members 20, 25 and 30 are made 40 of hard, wear-resistant material, and are capable of withstanding a long period of wear, these parts are readily replaced when worn merely by removing the metallic shuttle eye 7 from the shuttle body and slipping 45 the parts 20 and 30 from off the end of the pin 25. If the pin be worn it may now be withdrawn, a new pin substituted and new parts 20 and 30 slipped onto the lower part of the pin, and then the assembled structure is 50 stored to its position in the shuttle body.

In Fig. 8 the lower tension element is shown as a simple rectangular block 20^a having its upper edge 23^a slightly rounded or bevelled. This form of block, rather than that of Fig. 55 7, may be used with some types of shuttle eye.

In Fig. 9, the upper tension element 30^a is substantially like that of Fig. 6 except that the guide member 34^a is circular instead of 60 semi-circular. This form may be preferred, when the eye is of a nature to permit its use, since it is somewhat easier to make than that shown in Fig. 6.

In Fig. 10 the upper tension element 30^b is 65 of substantially rectangular contour, but

preferably has rounded edges to avoid cutting the yarn. In certain types of shuttle eye, this rectangular tension element is desirable. When elements of the type shown in Figs. 9 and 10 are to be used, the shuttle eye may be provided with complementary recesses to accommodate these elements.

The parts constituting this new tension device are of very simple form and easy to manufacture and apply, they are light in weight and take up but little room in the shuttle body and in no way interfere with the automatic threading operation. Moreover the yarn is tensioned uniformly, regardless of the direction of motion of the shuttle, the tension does not vary with variation in weather conditions, and the tension device is readily adjustable to accommodate yarns of a wide range of diameters.

While I have herein disclosed certain specific embodiments of the invention by way of example, I wish it to be understood that various other changes in shapes, proportions of parts, materials employed, and relative arrangement of the parts, may be made without departing from the spirit of the invention.

I claim:

1. In combination with a shuttle eye of self-threading type, a tension device comprising a pair of hard, wear-resistant, relatively 95 movable members adapted to receive a yarn between them, and adjustable means for urging one of said members toward the other whereby to oppose the free movement of the yarn, said members being independent of the shuttle eye and freely removable and replaceable without disturbing the setting of said adjustable means.

2. A tension device for use with a weaving shuttle having a removable eye of self-threading type, said tension device comprising a pair of relatively movable yarn-engaging elements disposed below the shuttle eye in a cavity in the shuttle body and retained in position solely by the superposed shuttle eye.

3. A tension device for use with a weaving shuttle having a removable shuttle eye, said device comprising a wear-resistant yarn support which seats in a cavity in the shuttle body, a friction-shoe movable toward and from the support, and means carried by the shuttle eye for holding said support and shoe in proper relative position.

4. A tension device for use in weaving shuttles comprising a pair of hard and wear-resistant members having opposed flat surfaces between which the yarn passes in an angular path, and adjustable resilient means for urging one of said members toward the other, said members being removable without disturbing the setting of said adjustable means.

5. A tension device for use in a weaving shuttle, said device comprising a yarn sup-

- port, an annular friction-shoe having an under surface engageable with a yarn resting on the support, said friction-shoe having a socket in its upper side, and resilient means seated in said socket and urging the shoe toward the support, and means for adjusting said resilient means, the support and shoe being removable without changing the setting of the adjusting means.
6. A tension device for use in a weaving shuttle having a cavity therein, said device comprising a yarn support adapted to seat in the bottom of said cavity, a friction-shoe having an under surface engageable with a yarn resting on the support, said friction-shoe having a socket in its upper side, a section of rubber tubing seated in said socket, a shuttle eye adapted to fit into the upper part of said cavity, and means carried by the shuttle eye for adjustably compressing the rubber tubing.
7. A tension device for use in a weaving shuttle, said device comprising a yarn support and a friction-shoe, the shoe and support having aligned openings, a pin passing through said openings and constituting a guide for the shoe, a resilient element encircling the pin and bearing at one end against the shoe, the pin having a head providing an abutment for the other end of the resilient element, and means whereby the pin may be adjusted longitudinally whereby to vary the resilient pressure on the shoe, the yarn support and friction shoe being removable from the pin without changing the adjustment of the pin.
8. A tension device for use in a weaving shuttle, said device comprising a yarn support and a friction-shoe, the shoe and support having aligned openings, a pin passing through said openings and constituting a guide for the shoe, a section of rubber tubing encircling the pin and having its lower end seated in a socket in the shoe, the pin having an enlarged cylindrical head against which the upper end of the tube abuts, the peripheral surface of the head of the pin being screw threaded for engagement with a threaded opening in a fixed part whereby the position of the pin may be adjusted, the yarn support and friction shoe being removable from the pin without changing the adjustment of the pin.
9. In combination with a self-threading shuttle eye for weaving shuttles, said shuttle eye having a base provided with a longitudinal yarn guide channel provided with a vertical side wall, said wall extending forwardly beyond the end of the channel, a yarn-supporting plate at the forward end of the channel, said plate having a part seated in a rabbet in the base of the shuttle eye and a body portion having an upper surface disposed slightly above the bottom of the channel, said body portion having a diagonal rear

edge providing for the accommodation of the forward end of the side wall of the yarn channel.

10. In combination with a self-threading shuttle eye for weaving shuttles, said shuttle eye having a base provided with a longitudinal yarn guide channel provided with a vertical side wall, a yarn-supporting plate at the forward end of the channel, said plate having a part seated in a rabbet in the base of the shuttle eye and a body portion having an upper surface slightly above the bottom of the channel, said body portion having a diagonal rear edge, and a friction-shoe having a flat under surface opposed to the upper surface of the yarn-supporting plate, the diagonal edge of the body portion of the plate being beveled to facilitate entrance of yarn between the plate and friction-shoe.

Signed by me at Providence, Rhode Island, this sixth day of April, 1928.

FRED E. ADAMS.
